(57) **CLAIM**

I claim the ornamental design for a dome-shaped pet bed with ball motif, as shown and described.

DESCRIPTION

FIG. 1 is a front perspective view of a first embodiment of a dome-shaped pet bed with ball motif showing my new design;

FIG. 2 is a front elevational view of the pet bed illustrated in FIG. 1;

FIG. 3 is a right-side elevational view of the pet bed illustrated in FIGS. 1 and 2;

FIG. 4 is a rear elevational view of the pet bed illustrated in FIGS. 1-3;

FIG. 5 is a left-side elevational view of the pet bed illustrated in FIGS. 1-4;

FIG. 6 is a top plan view of the pet bed illustrated in FIGS. 1-5;

FIG. 7 is a bottom plan view of the pet bed illustrated in FIGS. 1-6;

FIG. 8 is a front perspective view of a second embodiment of a dome-shaped pet bed with ball motif showing my new golf ball design;

FIG. 9 is a front elevational view of the pet bed illustrated in FIG. 8;

FIG. 10 is a right-side elevational view of the pet bed illustrated in FIGS. 8 and 9;

FIG. 11 is a rear elevational view of the pet bed illustrated in FIGS. 8-10;

FIG. 12 is a left-side elevational view of the pet bed illustrated in FIGS. 8-11;

FIG. 13 is a top plan view of the pet bed illustrated in FIGS. 8-12;

FIG. 14 is a bottom plan view of the pet bed illustrated in FIGS. 8-13;

FIG. 15 is a front perspective view of a third embodiment of a dome-shaped pet bed with ball motif showing my new tennis ball design;

FIG. 16 is a front elevational view of the pet bed illustrated in FIG. 15;

(Continued)

FIG. 17 is a right-side elevational view of the pet bed illustrated in FIGS. 15 and 16;

FIG. 18 is a rear elevational view of the pet bed illustrated in FIGS. 15-17;

FIG. 19 is a left-side elevational view of the pet bed illustrated in FIGS. 15-18;

FIG. 20 is a top plan view of the pet bed illustrated in FIGS. 15-19;

FIG. 21 is a bottom plan view of the pet bed illustrated in FIGS. 15-20;

FIG. 22 is a front perspective view of a fourth embodiment of a dome-shaped pet bed with ball motif showing my new basketball design;

FIG. 23 is a front elevational view of the pet bed illustrated in FIG. 22;

FIG. 24 is a right-side elevational view of the pet bed illustrated in FIGS. 22 and 23;

FIG. 25 is a rear elevational view of the pet bed illustrated in FIGS. 22-24;

FIG. 26 is a left-side elevational view of the pet bed illustrated in FIGS. 22-25;

FIG. 27 is a top plan view of the pet bed illustrated in FIGS. 22-26;

FIG. 28 is a bottom plan view of the pet bed illustrated in FIGS. 22-27;

FIG. 29 is a front perspective view of a fifth embodiment of a dome-shaped pet bed with ball motif showing my new baseball design;

FIG. 30 is a front elevational view of the pet bed illustrated in FIG. 29;

FIG. 31 is a right-side elevational view of the pet bed illustrated in FIGS. 29 and 30;

FIG. 32 is a rear elevational view of the pet bed illustrated in FIGS. 29-31;

FIG. 33 is a left-side elevational view of the pet bed illustrated in FIGS. 29-32;

FIG. 34 is a top plan view of the pet bed illustrated in FIGS. 29-33;

FIG. 35 is a bottom plan view of the pet bed illustrated in FIGS. 29-34;

FIG. 36 is a front perspective view of a sixth embodiment of a dome-shaped pet bed with ball motif showing my new soccer ball design;

FIG. 37 is a front elevational view of the pet bed illustrated in FIG. 36;

FIG. 38 is a right-side elevational view of the pet bed illustrated in FIGS. 36 and 37;

FIG. 39 is a rear elevational view of the pet bed illustrated in FIGS. 36-38;

FIG. 40 is a left-side elevational view of the pet bed illustrated in FIGS. 36-39;

FIG. 41 is a top plan view of the pet bed illustrated in FIGS. 36-40; and,

FIG. 42 is a bottom plan view of the pet bed illustrated in FIGS. 36-41.

Any broken lines appearing in FIGS. 1-42 depict features of the pet bed that form no part of the claimed design.
